FIG. 2

Des. 191,726

PAGE 3

FIG. 3

FIG. 4

FIGURE 1 is a side elevational view of an anchor, showing my new design, the three other sides being substantially the same;

FIGURE 2 is a top plan view thereof;

FIGURE 3 is a bottom plan view thereof; and

FIGURE 4 is a vertical cross section taken on line 4-4 of FIGURE 1.

I claim:

The ornamental design for an anchor, substantially as shown and described.
